UNITED STATES PATENT OFFICE

129,157

DESIGN FOR A CHAIR

Carl W. Burst, Richmond Heights, Mo.

Application October 12, 1940, Serial No. 95,800

Term of patent 3½ years

To all whom it may concern:

Be it known that I, Carl W. Burst, a citizen of the United States, residing at the city of Richmond Heights, St. Louis County, State of Missouri, have invented a new, original, and ornamental Design for a Chair, of which the following is a specification, reference being had to the accompanying drawings, forming part thereof.

Fig. 1 is a plan view of a chair showing my new design;

Fig. 2 is a front elevational view;
Fig. 3 is a side elevational view;
Fig. 4 is a rear elevational view; and
Fig. 5 is a perspective view.

I claim:
The ornamental design for a chair, as shown.

CARL W. BURST.
